UNITED STATES PATENT OFFICE

163,390

JAR

Robert Hofmann, Inglewood, Calif.

Application May 3, 1950, Serial No. 9,686

Term of patent 7 years

(Cl. D86—10)

To all whom it may concern:

Be it known that I, Robert Hofmann, a citizen of the United States and a resident of Inglewood, in the county of Los Angeles and State of California, have invented a new, original, and ornamental Design for a Jar, of which the following is a specification, reference being had to the accompanying drawing, forming a part thereof.

Figure 1 is a perspective view of a jar showing my new design;

Figure 2 is an elevational view thereof; and

Figure 3 is a top plan view.

I claim:

The ornamental design for a jar, substantially as shown.

ROBERT HOFMANN.
